UNITED STATES PATENT OFFICE.

HEINRICH JACOB, OF FRIEDENAU, GERMANY, ASSIGNOR TO THE FIRM OF OPTISCHE ANSTALT C. P. GOERZ AKTIENGESELLSCHAFT, OF FRIEDENAU, NEAR BERLIN, GERMANY.

DROP PROJECTILE AND FUSE FOR SAME.

Application filed August 30, 1921. Serial No. 496,957.

(GRANTED UNDER THE PROVISIONS OF THE ACT OF MARCH 3, 1921, 41 STAT. L., 1313.)

To all whom it may concern:

Be it known that I, HEINRICH JACOB, a citizen of the German Republic, and resident of Friedenau, near Berlin, Germany, 5 have invented certain new and useful Improvements in and Relating to Drop Projectiles and Fuses for Same, for which I have filed applications for German patents, filed Oct. 30, 1915, and Nov. 5, 1915; for 10 Austrian patents, filed Mar. 30, 1917, and July 19, 1919; for Hungarian patents, filed Apr. 12, 1917, and July 30, 1919; for Czechoslovakian patent, filed Feb. 6, 1920; for Swedish patents, filed July 23, 1919, and 15 July 24, 1919; for Danish patents, filed July 25, 1919, and July 29, 1919, and of which the following is a specification.

This invention relates to a drop projectile particularly for use on aircrafts and to fuses 20 for same and has for its object to secure safe handling of said projectile and fuse and to allow adaptation to different requirements according to the special nature of the target against which the projectile 25 is to be used.

The invention is illustrated in several embodiments on the annexed drawings.

Fig. 1 shows in longitudinal section and partly in side elevation substantially diagrammatically a projectile in accordance 30 with this invention provided with two fuses, one at the front end and one at the rear end.

Fig. 2 shows a longitudinal section through the front end of the projectile, 35 and

Fig. 3 a cross section on the line 3—3 of Fig. 2.

Fig. 4 is a longitudinal section and partly side elevation of the rear end fuse of the 40 projectile and of the carrying parts of the projectile itself.

Fig. 5 is a top view on the rear end fuse.

Fig. 6 is a side elevation of a modified form of a projectile in accordance with the 45 invention provided with a front end fuse having a striker forming the point of the projectile.

Figs. 7 and 8 show on a larger scale longitudinal sections through the front end of 50 the projectile of Fig. 6: the two figures illustrating the parts of the fuse in different positions.

Figs. 9^a and 9^b are cross sections on the line 9—9 of Fig. 7 showing different posi-

tions of an adjusting ring, namely Fig. 9^a 55 the position corresponding to quick detonating of the charge and Fig. 9^b the position corresponding to slow detonating.

The projectile of Fig. 1 is provided with two fuses 1 and 2. The front end fuse 1 60 is shown as being screwed into a cavity at the front end of the shell of the projectile. This front end 3 of the shell is shown on the drawing as thick-walled, whereas the remaining part of the shell has only a thin 65 wall 4, a conical steering tail 5 being provided free from explosive and carrying steering surfaces 6.

According to Figure 2 the front fuse comprises a needle 7 and a hollow striker 8 carrying a percussion cap 9. The percussion cap is secured against contact with the needle point by a safety device comprising three weighted pendulums 10 rotatably mounted on pins 11 and adapted to be actuated by centrifugal force on rotation of the projectile. The pendulums 10 are interposed between the striker 8 and an undercut projecting ring 12 of the needle 7 which is adapted to enter into undercut recesses 70 of the pendulums. 13 and 14 are springs tending the former to keep the percussion cap 9 of striker 8 remote from the point of the needle 7 and the latter tending to keep the pin 11 remote from the recesses of the 75 pendulums 10. 15 is a peg adapted to become inserted transversely to the fuse and the needle therein securing when inserted interlocking of the projecting ring 12 with the recesses in the pendulums 10. 16 is a 80 casing for the fulminant to be ignited by the percussion cap 9 and adapted to ignite the explosive charge 17 and to so bring the projectile to explosion.

The rear end fuse 2 is of similar construction as the front end fuse 1. The rear end fuse is mounted on the back plate 18 of the explosive chamber of the projectile. The needle is designated 19; in the embodiment shown in Fig. 4 of the drawing the needle is provided with two points 20, 21 the needle points cooperating with two percussion caps 22, 23 respectively; two points and two percussion caps being provided in order to raise the certainty of igniting. The needle 19 is in this instance constructed as a weighted bolt in order to allow it to fulfill the function of a striker. 24 is a projecting undercut 95

100

105

ring of the needle-striker adapted to interlock with corresponding recesses within the pendulums 25 of a centrifugal safety device. 26 is a spring tending to keep the needle points out of contact with the percussion caps. 27 is a casing for a fulminant adapted to become ignited itself by the percussion caps and to ignite the explosive charge. 28 are headed screws fixed in plate 18 designed 10 for conveniently mounting the fuse on plate 18. To this end the main body or casing of the fuse is provided with a flange 29 provided with slots 30 with enlarged ends allowing passing of the heads of screws 28. By 15 slightly rotating the fuse body with the flange 29 it becomes firmly connected with plate 18. For preventing unintentional loosening of the fuse from plate 18 flange 29 is provided with a plate spring 31 with 20 pin 32 adapted to snap into a recess of flange 29. 33 is a screw ring for securing plate 18 in position and 34 a peg for keeping the centrifugal pendulums 25 in interlocked position with the projecting ring 24 25 of the needle-striker 19 during transportation and handling of the fuse and projectile.

The handling and operation of the fuses and projectile is as follows:

During handling and transportation the 30 fuses are set to safety by inserting pegs 15 and 34. When this is done even quick rotation of the projectile is unable to produce a swinging out of the pendulums 10 and 25, this being prevented by interlocking of the 35 undercut projections 12 and 24 of the needles with the cooperating recesses of the pendulums 10 and 25 respectively of the pendulums. Before releasing the projectile on an aircraft the pegs 15 and 34 are pulled 40 out whereupon springs 14 and 26 withdraw the needles from interlocking with the pendulums which however continue to prevent the needle points to reach the corresponding 45 percussion caps as long as they are not swung out by centrifugal force. During the falling down of the projectile to the ground the projectile is rotated owing to a propeller like action of the steering surfaces 6. Under 50 the influence of centrifugal force produced by such rotation the pendulums 10 and 25 swing out and do no longer prevent the access of the needle points to the percussion caps. In the case of the front end fuse the 55 striker 8 with its percussion cap 9 is advanced towards the needle point as soon as the velocity of the projectile on impact on a target has sufficiently diminished whereas in the case of the rear end fuse the weighted needle forming itself the striker is advanced 60 towards the percussion caps when the projectile has undergone sufficient retardation of its velocity to allow the striker needle 19 to overcome the resistance of spring 26.

Under normal conditions it is only in the 65 case of very heavy projectiles with big

masses of explosive necessary to provide two fuses one at the front end of the projectile and one at the rear end. In most cases one fuse is sufficient to properly detonate the 70 whole charge of the projectile.

In the case of light projectiles, say of about 12 kg., it is however desirable to make at will the fuse acting on retardation of the velocity of the projectile as in the case of the above described fuses or on impact of the projectile on the target. A projectile with such a fuse is illustrated in Figs. 6-9^b of the drawings. The main difference between the front end fuse of Fig. 2 and that of Figs. 7 and 8 consists therein that the 75 needle of Fig. 2 is extended so as to penetrate the front end of the fuse. This makes it possible to use the needle on the one hand if locked in position in the same way as in the case of Fig. 2 and on the other hand, if given free for shifting on impact on the target as striker, which on impact instantaneously ignites the percussion cap.

In Figs. 7-9^b the needle-striker for quick igniting is designated 35 and the hollow 80 striker for slow igniting 36. The pendulums of the centrifugal safety device are 37; they are provided with recesses 38 cooperating with a projecting ring 39 of the needle-striker. The needle-striker is provided with a head penetrating the front end 85 of the fuse and so forming the point of the projectile. The head of the needle-striker is provided with projections 40 and recesses 41 alternating with each other. 42 is a 90 spring tending to keep the projecting ring 39 out of engagement with the recesses 38 of the pendulums. 43 is a spring tending to 95 keep the percussion cap 44 of the striker 36 out of contact with the point of the needle 100 35. 45 designates a rotatable adjusting ring, forming tight joint with the head of the striker 35 and being provided with projections and recesses 46, 47 corresponding to 105 the projections and recesses 40, 41 of the head of the needle-striker and adapted to be brought at will into alignment with them, so that depending from the adjustment of 110 the ring the striker 35 is locked against being shifted towards the percussion cap 44, namely in the case where the projections of 115 the ring are in line with the projections of the head of the striker or given free for such shifting movement, namely in the case where the projections of the ring are in line with the recesses of the head of the striker. 48 is a casing for the fulminant of the fuse 120 adapted to detonate the charge 49 of the projectile. 50 is a peg adapted to be transversely inserted into the point of the fuse and 125 51 a protecting cap for the front end of the fuse. 52 is a plate spring securing the ring 45 against an unintentional displacement. 53 is a mark on the outside of the fuse and 130 54, 55 are two marks on ring 45 allowing to

control the adjustment of the ring with regard to the fixed mark 53.

The operation of the fuse is as follows:

During transporting, may it be of the fuse alone or of a projectile provided with a fuse, the protecting cap 51 is put on the front end of the fuse and secured thereon by peg 50. On inserting peg 50 which penetrates striker 35 the projection 39 of the 10 striker is brought to interlocking with the recesses 38 of the pendulums 37, so that the fuse is set to safety. If it is intended to throw the bomb against a target from an aircraft the peg is pulled out and thereby 15 the needle-striker released from interlocking with pendulums 37 and the fuse set to quick or slow igniting by adjusting ring 45. During its falling to the ground the bomb is brought into rotation by suitable steering 20 surfaces and the pendulums 37 swung out. Depending from the adjustment of ring 45 the bomb is ignited on impact or on retardation of the velocity of the bomb. In the first case the needle-striker 35 is advanced 25 towards the percussion cap 44 which in this case is stationary. In the second case the projections 40 of the needle-striker are in line with the projections 46 of the adjusting ring, so that the needle-striker in spite 30 of the impact on the target is prevented from advancing towards the percussion cap. However on retardation of the velocity of the projectile the hollow striker 36 advances 35 towards the needle-striker 35 over-coming the pressure exerted by spring 43 and the percussion cap 44 is brought into contact with the needle point causing explosion of the bomb.

What I claim is:

- 40 1. In a drop projectile a fuse comprising a needle slidably arranged therein, a centrifugally actuated safety device adapted to interlock with said needle, a spring tending to withdraw said needle from interlocking with the centrifugal safety device and a peg adapted to be transversely inserted into said fuse and to retain if inserted said needle and centrifugal safety device in interlocked position.
- 45 2. In a drop projectile a fuse comprising a needle slidably arranged therein, a centrifugally actuated safety device adapted to interlock with said needle, a spring tending to withdraw said needle from interlocking with the centrifugal safety device, a peg adapted to be transversely inserted into said fuse and to counteract said spring and to push the needle towards the centrifugal safety device so as to become interlocked therewith and a hollow striker normally held out of operative contact with said first named needle by said centrifugal safety device but adapted to advance towards it on retardation of the velocity of said first 55 named needle.

3. In a drop projectile two fuses one at the front end and the other at the rear end of the projectile each fuse comprising a needle slidably arranged therein, a centrifugally actuated safety device adapted to 70 interlock with said needle and a peg adapted to be transversely inserted into said fuse and to retain if inserted said needle and centrifugal safety device in interlocked position.

4. In a drop projectile having an explosion chamber closed at its rear end by a plate, two fuses, one forming the point of the projectile and the other mounted on the rear side of rear wall of the explosion chamber of the projectile, each fuse comprising a needle slidably arranged therein, a centrifugally actuated safety device adapted to interlock with said needle, and a peg adapted to be transversely inserted 80 into said fuse and to retain if inserted said needle and centrifugal safety device in interlocked position, the projectile being provided at its rear end with a hollow conical steering tail detachably connected with the body of the projectile and covering the rear 85 plate of the explosion chamber and enclosing the rear end fuse.

5. In a drop projectile a fuse forming the point of the projectile comprising two 90 strikers slidably mounted within the fuse one of them penetrating the point of the projectile, a centrifugally actuated safety device adapted to keep the two strikers out of operative contact with each other so as to set the fuse at safety and means adapted 95 to lock the striker penetrating the point of the projectile in position independently from the other striker leaving only the latter ready for action.

6. In a drop projectile a fuse forming the point of the projectile comprising two 100 strikers slidably mounted within the fuse one of them penetrating the point of the projectile, a centrifugally actuated safety device adapted to keep the two strikers out of operative contact with each other so as to set the fuse at safety, and an adjusting ring, the adjusting ring and the striker penetrating the point of the projectile each being 105 provided with cooperating projections and recesses corresponding to each other, so that depending from the adjustment of the ring either the projections or the recesses of the striker are in line with the projections of the ring so as to either lock the striker in position or to allow it to advance towards the second striker.

7. In a drop projectile a fuse forming the point of the projectile comprising two 110 strikers slidably mounted within the fuse one of them penetrating the point of the projectile, a centrifugally actuated safety device adapted to keep the two strikers out of operative contact with each other so as to set the fuse at safety, said centrifugal safety 115 device 120 125 130

device adapted to interlock with the striker penetrating the point of the projectile, means adapted to secure interlocking of said striker and centrifugal device so as to set the fuse at safety, and means adapted to lock the striker penetrating the point of the projectile in position independently from the other striker leaving only the latter ready for action on actuation of the centrifugal device.

8. In a drop projectile a fuse forming the point of the projectile comprising two strikers slidably mounted within the fuse one of them penetrating the point of the projectile, a centrifugally actuated safety device adapted to keep the two strikers out of operative contact with each other so as to set the fuse at safety, and an adjusting ring forming a movable intermediate portion 20 of the outer surface of the fuse closely adjoining the exterior surface of the striker penetrating the point of the fuse, said adjusting ring and the last named striker being each provided with cooperating projections 25 and recesses inside the fuse, the adjustment of said ring allowing to bring either its projections or its recesses in line with the projections of the striker so as to either lock the striker in position or to allow it to 30 advance towards the second striker on impact provided release of the centrifugal device.

9. A fuse for drop projectiles designed for being inserted in and connected to the body 35 of the projectile comprising a needle slidably arranged therein, a centrifugally actuated safety device adapted to interlock with said needle, a spring tending to withdraw said needle from interlocking with the centrifugal safety device and a peg adapted to become transversely inserted into said fuse and to retain if inserted said needle and centrifugal safety device in interlocked position.

40 45 10. A fuse for drop projectiles designed for being inserted in and connected to the body of the projectile comprising a needle slidably arranged therein, a centrifugally actuated safety device adapted to interlock

with said needle, a spring tending to withdraw said needle from interlocking with the centrifugal safety device, a peg adapted to become transversely inserted into said fuse and to counteract said spring and to push the needle towards the centrifugal safety device so as to become interlocked therewith and a hollow striker normally held out of operative contact with said first named needle by said centrifugal safety device but adapted to advance towards it on retardation of the 60 velocity of said first named needle.

11. A fuse for drop projectiles designed for being inserted in and connected to the body of the projectile comprising two strikers slidably mounted within the fuse 65 one of them penetrating the forward end of the fuse, a centrifugally actuated safety device adapted to keep the two strikers out of operative contact with each other so as to set the fuse at safety, and means adapted to 70 lock the striker penetrating the point of the fuse in position independently from the other striker.

12. A fuse for drop projectiles designed for being inserted in and connected to the body of the projectile comprising two strikers slidably mounted within the fuse one of them penetrating the forward end of the fuse, a centrifugally actuated safety device adapted to keep the two strikers out of operative contact with each other so as to set the fuse at safety, and an adjusting ring provided with projections and recesses, the striker penetrating the point of the fuse likewise provided with corresponding projections and recesses, the projections of the ring adapted to be brought at will in line with the projections or with the recesses of the striker so as to either lock the striker against longitudinal shifting or to give it free for advancing towards the second striker.

In witness whereof I have hereunto set my hand in presence of two witnesses.
